UNITED STATES PATENT OFFICE

LELAND G. PLANT, OF CHICAGO, ILLINOIS

LOCOMOTIVE BOILER WASHING PLANT

Application filed July 26, 1928. Serial No. 295,577.

My invention relates to a complete unitary structure for effectively disengaging the entire steam content in the discharge from locomotive boilers at a terminal, condensing all of 5 this steam with fresh locomotive filling water, storing the resultant hot filling water and condensed steam in a reservoir whose outer circumference is insulated from the atmosphere and storing the water discharged from 10 the locomotive boilers, for use in washing locomotives, after separating heavy solid particles therefrom, in a reservoir whose outer circumference is cooled by exposure to the surrounding atmospheric temperature.

15 All of these features are fundamentally desirable to the most effective utilization of the discharged products which can be reclaimed from locomotive boilers upon arrival at a terminal and for many years the several operations 20 above described have been individually and collectively practiced. But in such practices, the results have always been attained in two or more separate pieces of apparatus connected only by pipes whereas I propose to 25 accomplish all of these operations in a unit constructed as a single self-contained structure of novel design. The unique structural features of my invention not only afford a more economical construction but also provide 30 the means for functioning more efficiently in respect to each operation involved than has been possible in the separate apparatus units hitherto employed.

35 Preliminary to describing the structural details of my invention and the manner in which it operates, attention is called to the present situation at locomotive terminals and conditions which make the distinctive features claimed for this invention of real value.

40 Locomotives have now increased in size and capacity to such an extent that the investment in each unit compels all large railway systems to utilize these locomotives more intensively by reducing wherever possible the time that 45 they are held out of service for such routine operations as washing boilers, although Federal regulations stipulate that all locomotive boilers be emptied and washed at intervals not exceeding thirty days while in active service and in many localities the water avail-

able for boiler use is so impure that locomotives must be washed out every few days.

Locomotives arriving at a terminal under steam, contain a large quantity of water at steam temperature which it is customary to 55 reclaim by drawing off through the blow-off valve at a low point in the boiler, the steam pressure on top of the water in the boiler serving to force the water out through a blow-off line to a separator ordinarily consisting 60 of a cylindrical drum in which the heavier solid particles, or sludge, settle to the bottom and the steam liberated from the water now at atmospheric pressure or at slight vacuum rises to the top and is thence drawn into a condenser of the jet type; that is, a drum or series 65 of drums in which a jet of cold water comes in direct contact with the steam. If the condenser action is correctly balanced it may induce a slight vacuum effective in the separator with which it is connected. The effect of 70 this vacuum is to increase the quantity of steam liberated by the water from the locomotive boiler as it is discharged into the separator. From the separator it is customary 75 to drain the water into a separate reservoir where it is available for use in washing locomotive boilers. The sludge or solid matter collecting in the base of the separator is periodically removed either manually or automatically. From the condenser, the fresh 80 water which has become heated in contact with the condensing steam, together with the condensed steam, drains by gravity to another reservoir from which hot water is 85 drawn for filling locomotive boilers after they have been washed out.

From the foregoing, it will be observed 90 that the equipment required for reclaiming the blown-off products from locomotive boilers and utilizing these as a source of hot water for washing and filling locomotive boilers as now practiced, involves first a separator, then a condenser and two reservoirs, one for 95 washing water and the other for filling water at as high a temperature as it is possible to maintain with the sources of heat available. The object of heating the filling water by means of steam reclaimed from locomotive boilers as they are emptied is to 100

reduce the amount of fuel that must be burned on other locomotives which have been refilled and the time required to develop a working steam pressure on these locomotives. Ordinarily, it is practical to maintain a temperature of 180 degrees F. in the filling water reservoir derived entirely from the latent heat in steam flowing to the condenser. The temperature of water flowing from the separator to the washing water reservoir is approximately the same. But while it is desirable to have hot water for washing locomotive boilers to avoid the severe strains induced by contraction of the hot sheets that would be caused by washing with cold water, it has not been found practical to use water for washing boilers at a temperature above 135 degrees F. on account of the danger of scalding men employed to wash the boilers. For this reason, it is necessary to reduce the temperature of water in the washing water reservoir before it can be used for washing boilers.

In the systems described which are in common use today, consideration must be given to maintaining the highest possible temperature in the filling water reservoir and also to moderating the temperature of water in the washing water reservoir. These considerations necessitate housing the filling water reservoir to protect it from the cooling effect of exposure to the atmosphere, and also housing both the separator and the condenser apparatus. While it is not necessary to house the washing water reservoir, this is ordinarily done so that the entire apparatus can be located in one building. To reduce the temperature of water from the washing water reservoir to a degree suitable for washing purposes, it is also customary to introduce a quantity of fresh cold tempering water, the amount being automatically controlled by a thermostatic regulator. However, this involves a waste of water since the volume of water delivered to the washing water reservoir would alone be ample for washing purposes. Another disadvantage encountered in the systems now in use as above described is found in the dimensions of the separator which are necessarily limited for reasons of structural economy. The area of the water surface from which the steam is liberated is thus restricted resulting both in the retention of steam by the water flowing to the washing water reservoir and the entrainment of foul water particles in the steam flowing to the condenser so that under certain conditions an undesirable quantity of foul water may be carried into the filling water reservoir.

In the construction of such systems as have been described which are now in general use, the cost of housing the reservoirs together with the separator, condenser, pipe connections and pumps, for delivering the filling

and the washing water to the enginehouse represents a considerable part of the cost of these systems whether an individual building is constructed for this purpose, or the apparatus be contained in part of a larger building such as the stationary boiler plant or power house which is a part of the terminal. Furthermore, such a building usually being of rectangular construction if designed to shelter two circular reservoirs of large capacity will necessarily occupy considerable space and is inherently uneconomical in respect to the utilization of such space. Interconnections between the separator, the condenser, or condensers, (which may be mounted in tandem) and the washing and filling water reservoirs, which are connected respectively to the separator and condenser, are necessarily expensive to fabricate and maintain. Another item of maintenance expense incident to the operation of such systems is the removal of scale accumulating in the condenser drum and adhering to the walls of this structure, often making this a difficult and expensive operation to perform aside from the inconvenience and expense occasioned by interrupting the operation of the system while scale is being removed from the condenser.

With these considerations in mind, I have devised a single, self-contained structure serving as a separator, a condenser and a partitioned reservoir for the storage of locomotive filling and washing water, which structure can be advantageously located outdoors without housing or insulation since the washing water compartment surrounds the filling water reservoir and serves to insulate it, while at the same time presenting a more extended exterior surface to atmospheric cooling influences than in a non-partitioned circular tank of the same capacity, the effect being to increase the cooling effect of atmospheric temperatures upon the washing water in lieu of tempering this water by admission of additional fresh cold water. In my invention, the entire horizontal, cross-sectional area of the washing water reservoir becomes a liberating surface for the separation of steam from water discharged through locomotive blow-off valves and delivered to the washing water compartment. This not only insures the separation of all steam particles from the washing water but the effective separating area is so large that the velocity of steam rising from the water is reduced to a point that eliminates the possibility of its entraining the blown off water particles with their impurities and carrying them over into the filling water reservoir which comprises the center or core of my structure. The domed roof of this structure, induces inward flow of the vapors rising from the disengaging surface of the filling water, and itself constitutes a condenser for the liberated

steam, although it is preferably supplemented by cold water jets located at its apex. Another condensing medium of which I avail myself is the entire water surface in the filling water reservoir, which may be mechanically agitated to accelerate this condensing effect.

In my invention, heavier solid particles, or sludge, in water discharged from locomotive boilers is accumulated between sloping partitions, or sludge baffles, in the washing water reservoir, which converge to a point near the bottom of the reservoir directly below the inlet to this reservoir. From this point, the sludge may be discharged to a sewer at intervals, or in a slow continuous stream. Removal of scale accumulating on the walls of the condenser chamber is facilitated by providing a removable cylindrical lining which is of somewhat smaller diameter than the outer wall of the condenser chamber and forms, with the latter, an uptake through which steam that accumulates beneath the roof from the outer compartment, or separator, may pass upwardly in chilling impingement against said walls on its way to the condenser jets, so that condensation and precipitation into the filling water reservoir are contributed to by the roof surfaces, the condensing chamber surfaces, the water jets, and the filling water surfaces. Condensation is preferably accelerated by one or more horizontal baffles, or splash plates which tend to break up water streams from condenser jets. The flow of water through these condenser jets is governed by two conditions; first, it is governed by the temperature registered in a by-pass tube which, while it becomes filled with steam as soon as any quantity of exhaust steam is liberated from the outer reservoir, or separator, is nevertheless so removed from the path of the condensing water jets that it will not be sprayed by the latter and will therefore not be subjected to the insulating precipitate which is found so objectionable in thermostats located in reach of the condensing spray. Second, the condenser jet is governed by the height of water in the filling water reservoir as registered in a riser pipe connected to the filling water reservoir and located in a building adjacent to the reservoir where all control valves to the condenser jets may be conveniently located in a single panel mounted against the wall. The distinctive features of my invention will be more readily understood by referring to the illustrative embodiment shown in the accompanying drawings in which—

Figure 1 is a plan view of that portion of a locomotive terminal with which my invention is immediately concerned, portions of the blow-off, wash-out, and refill lines which connect the reservoir with the locomotive stall being omitted;

Figure 2 is a vertical sectional view of the reservoir, the plane of the section being substantially coincident with that of the blow-off connection;

Figure 3 is a side elevation of the portion of the system shown in Figure 1, as viewed from the front of Figure 1 and at right angles to Figure 2;

Figure 4 is a detail view of the water control connections responsive in part to the thermostat in the steam by-pass and in part to the water level in the filling water compartment of the reservoir; and

Figure 5 is a view on an enlarged scale in vertical section parallel with the picture plane of Figure 2 and showing the details of the condenser chamber.

Referring in detail to the particular embodiment of the invention here selected, for purposes of illustration, 1 and 2 represent respectively outer and inner concentric walls rising from a common base 3 of the reservoir and dividing the latter into an inner compartment 4 for the storage of locomotive filling water and an outer compartment 5 for the storage of locomotive wash-out water. The partitions 1 and 2 in the relation illustrated will provide approximately identical capacities in the two storage compartments 4 and 5 but obviously these relative capacities may be varied at will. An important feature of this invention resides in the fact that with the wash-out water compartment 5 exposed externally to atmospheric cooling influences and the filling water compartment 4 surrounded by said compartment 5, the loss of heat will be induced in the wash-out water where it is desirable and will be largely prevented in the filling water where cooling would be undesirable.

Surrounding the reservoir is a roof 6, serving in common to both compartments, preferably domed in its design and providing over the compartments, a space which serves as a communication between the compartments, induces flow of volatiles which disengage from surface of the wash-out water, inwardly, so that when condensed they will be precipitated into the filling water compartment, and affords an effective condensing influence upon these volatiles. To ensure ample condenser efficiency above the filling water, roof 6 is surmounted by a condensing chamber 7, into which the volatiles from blown off products will be directed by the shape of the roof. Condenser 7 is equipped with a suitable number of spray nozzles, typified in the present instance by nozzle 8, which will function more or less constantly in order to take care of the exhaust steam arriving through exhaust pipe 9 from power apparatus such as pumps 10 and 11; a water jet 12, which will be normally inactive but automatically releasable in response to an accumulation of hot volatiles from the disen-

gaging surface of the washing water compartment 5, for instance, by having the thermostat 13 located in a by-pass 14 which leads from an elevated point beneath the roof 6, 5 into the upper portion of the condenser 7; and the water spray or discharge nozzle 15 which while assisting in the condensation of such volatiles as may be present when it functions, is primarily for the purpose of replen- 10 ishing water in the filling compartment 4 when the latter becomes exhausted to a pre-determined low level, to which end the said nozzle 15 will be brought under a water level control to be described.

15 The controls for the water nozzles 12 and 15 which are responsive respectively to the thermostat 13 in the vapor by-pass 14 and a low water condition, will preferably be located on a baseboard or wall remote from 20 the reservoir where will also be found such other needed controls as may be conveniently associated with them. Thus 16 represents a hydrostatic standpipe connected through its bottom branch 16-A with the filling water 25 compartment 4 vented at top so that water will always stand in this pipe at the same level in which it stands in the filling compartment.

17 represents an outside float so connected 30 with the valve 18 in the branch 19-B that whenever the level of water in standpipe 16 is lowered sufficiently to empty the float 17, valve 18 will automatically open and permit the flow of fresh water through pipe 15-A 35 to the water nozzle 15 and this flow will continue until water has been replenished in the filling compartment 4 to a desired level of safety. Similarly, 20 represents an outside float, in communication with an elevated 40 point in the standpipe 16, so connected with the normally open valve 21 in the pipe 8-A that supplies the normally running nozzle 8 that whenever the water reaches a level in filling water compartment 4 which would 45 cause waste, float 20 fills and its weight closes the valve 2 until such time as the water level may again fall in the compartment 4. Finally, we have in the group of controls, a thermostatically controlled valve 22, whose actuating means 22-A is subjected through the thermopile connection 13-A with the thermostat 13 in such manner that whenever the thermostat 13 registers the presence of steam vapors in the by-pass 14, valve 22 will be 50 open to release condensing water through the spray nozzle 12.

23 represents an overflow connection between the compartment 4 and the compartment 5 through which excess filling water 60 may escape into the washing water compartment in case of need and 24 represents an overflow and escape connection from the washing water compartment and into the sewer connection 25. Overflow connection 24 65 is preferably on a lower level than the con-

nection 23 so that the flow of waste water is always toward the sewer and never from the washing water compartment into the filling water compartment.

Inasmuch as the reservoir constitutes a 70 unitary, self-contained, enclosed structure, it will be desirable to employ at some convenient place, for instance in assembly cover 26 of the condenser 7, a vent 27 which while normally closed, will open either under the 75 condition of excessive vacuum within the reservoir or excessive steam pressure therein, said valve being arranged to discharge, for instance, through the vent pipe 27-A.

The condenser chamber which surmounts the roof 6 will preferably embody in its structure not only its outer wall but a concentric inner wall 7-A, spaced from wall 7 sufficiently to leave an uptake passage 7-B for volatiles accumulating beneath the roof 6, 85 said inner wall 7-A terminating short of the upper end of the condenser chamber so as to afford communication between the uptake 7-B and the central space in which the spray nozzles act; and said inner wall also depends below the lower end of the outer wall 7 and beneath the apex of the roof in order to direct the volatiles into the uptake. With the spray nozzles playing in the central space of the condenser and keeping the 90 inner wall 7-A cool and the outer wall 7 exposed to the cooling influences of atmosphere, it will be seen that condenser capacity will be contributed to largely by impingement of the vapors against these walls 7 and 100 7-A. Intercepting the downward path of the water sprays and spaced a suitable distance beneath the lower end of the inner wall 7 is a baffle 7-C substantially horizontal and serving the function of breaking up the water 105 jets. Surrounding the water spray condenser in position to prevent splashing of the interrupted water sprays over into the water washing compartment is a depending apron 28.

The aggregate of condensing influences 110 obviously will include the roof surfaces, the surfaces of the depending apron 28, the surfaces of the spaced condenser chamber walls, the jets of water from the nozzles, the baffles 7-C and even the surface of the water in the 115 filling water compartment.

The disengaging surface for the volatiles will consist of the entire surface area of water in the washing water compartment 5 and the opportunity for the volatiles from this relatively large disengaging surface, to flow inwardly to the condensing region over the filling water compartment is substantially uniform throughout the washing water compartment.

The separating, condensing, and sorting apparatus herein described may be connected with the locomotive stall or stalls through the conventional blow-off, wash-out, and refill connections. 29 represents the portion of a 120 125 130

blow-off connection adjacent the reservoir which terminates in a downwardly directed spout 30, discharging into the outer compartment of the reservoir and adapted to be shut off at will through means of a valve 29—A. Blow-off connection 29 also communicates through valve 29—A and pipe 29—B with the sewer connection 25 and the latter is provided with the usual vent 25—A for steam as a means for relieving excessive pressure. Vertically beneath the spout 30, the outer compartment of the reservoir has a separator chamber 31 defined by downwardly converging baffles 32 and having adjacent to its lower ends, a sludge discharge 31—A. The entire blown-off products from the locomotive are delivered into the space between the baffles 32, where the sludge or solid matters in suspension are permitted to settle and pass out either gradually or continually as may be preferred, through the discharge 33 and the water escaping over the upper limits of the baffles into the annular outer compartment 5 where the relatively large steam disengaging space is developed, heat is largely transferred through the wall 2 to the filling water in the compartment 4, and the process of saving the heat units through means of volatiles is generally favored as already pointed out.

33 represents a pipe leading from the washing water compartment 5 to the washout pump 10 by which washing water is discharged toward the locomotive stall through pipe 34; and 35 represents a pipe leading from the filling water compartment 4 to the pump 11 by which filling water is discharged toward the locomotive stall through a pipe 36. 37 and 38 represent emergency discharge connections through means of which compartments 4 and 5 may be emptied when necessary. 39 represents an emergency water supply connection to the outer compartment 5 which will permit the supply of water to the latter in case blow-off water is not available. 40 represents an emergency steam heating plant that may be used to bring up the temperature of the filling water in compartment 4 in case of necessity, said pipe having its discharge end submerged in compartment 4 and equipped with a nozzle and vent usually referred to in the art as a noiseless heater.

I claim:

1. A locomotive boiler washing and refilling apparatus, comprising a first compartment adapted to receive and separate the volatiles from the water in products blown off from locomotives, and also to store said water for washout purposes; a second compartment adapted to store filling water, said compartments having a common wall separating them and terminating above the maximum water level of either compartment and a roof common to both compartments spaced above said wall and leaving between the wall

and roof a passage corresponding in horizontal dimension substantially to that of the wall permitting free flow from the first compartment to the second compartment of volatiles disengaged in said first compartment, 70 said roof and the confines of and the water surface in said second compartment constituting a surface condenser for said volatiles; and a condenser receiving and delivering as condensate to the second compartment, volatiles that are not precipitated by said surface condenser. 75

2. A locomotive boiler washing and filling apparatus, comprising a first compartment having a connection through which it receives products blown off from locomotives, and constituting a combined washout water storing and a volatiles-disengaging space; a second compartment constituting a filling water storing and volatiles-condensing space, 80 said compartments having a common confine which separates them up to a level higher than the maximum water levels in the two compartments, and a roof common to both compartments spaced above said common 90 confine and establishing communication over substantially the whole horizontal dimension of said confine between said compartments through which volatiles disengaged in the first compartment may flow 95 freely into the space above the water in the second compartment, and there enter into condensing contact with the surface of the filling water and the roof and other confines of said second compartment; and a fresh 100 water condenser located above the water level in said second compartment, receiving volatiles from said second compartment that are not condensed by such surface contact and delivering the same as condensate to said 105 second compartment.

3. A locomotive washing and filling apparatus, comprising first and second compartments partitioned one from the other to a level above the maximum water level in 110 either of said compartments, and having a roof common to both said compartments spaced above the level to which they are partitioned and providing a top confine for a horizontally extensive volatiles flow space 115 through which said compartments communicate, and forming with the confines of said compartments in a closure tight against the escape of volatiles from said compartments; the first compartment having a delivery connection through which it receives products blown off from locomotive boilers and constituting a combined volatiles-disengaging and washout water-storage space; the second compartment constituting a combined filling water-storing and volatiles-condensing space; and said second compartment also having a fresh water condenser receiving from said second compartment, volatiles that are not precipitated by surface 130

condensation therein and delivering the same to said second compartment as condensate.

4. A locomotive boiler washing and refilling apparatus, comprising a first compartment adapted to receive and separate the volatiles from the water in products blown off from locomotives, and also to store said water for washout purposes; a second compartment adapted to store filling water and having communication with the first compartment above the maximum water line of the compartments, said communication permitting free flow from the first compartment to the second compartment of volatiles disengaged in said first compartment, and the confines of and the water surface in said second compartment constituting a surface condenser for said volatiles; and a condenser receiving and delivering as condensate to the second compartment, volatiles that are not precipitated by said surface condenser; the first compartment being constructed with a partition defining a sludge-confining space, and having an outlet for washout water located on the opposite side of the partition from said sludge-confining space, whereby the sludge is baffled against access to said outlet.

5. A locomotive blowoff, washout, and refill apparatus, comprising a first compartment having a connection through which it receives products blown off from locomotives, said first compartment including a separated sludge-receiving space into which said products are delivered, a washout water storing space outside of said sludge receiving space, a volatiles-disengaging space above said washout water storing space, a sludge discharge leading from said sludge-receiving space, and a washout water discharge baffled from said sludge receiving space; a second compartment adapted to store filling water, partitioned from said first compartment to an elevation higher than the maximum water level of either compartment, but having free communication for the flow of volatiles from the first compartment above said level; a top closure for said second compartment, comprising confines which together with the surface of the water in said second compartment constitute a surface condenser; and a water supply adapted to augment the condensation of volatiles in said second compartment.

6. A locomotive boiler washing and refilling apparatus, comprising a first compartment adapted to receive and separate the volatiles from the water in products blown off from locomotives, and also to store said water for washout purposes; a second compartment adapted to store filling water, said compartments having top, side and bottom confines which completely close them against the escape of volatiles, including a partition-

ing confine common to both compartments which terminates above the maximum water line in either compartment but beneath their top confines, thereby leaving between the compartments an upper horizontally extensive communication permitting free flow from the first compartment to the second compartment of volatiles disengaged in said first compartment, and the confines of and the water surface in said second compartment constituting a surface condenser for said volatiles; and a condenser receiving and delivering as condensate to the second compartment, volatiles that are not precipitated by said surface condenser; said compartments existing in a single structure and the partitioning confine of said compartment leaving them in heat transfer relation one to the other.

7. A locomotive boiler washing and refilling apparatus, comprising a first compartment adapted to receive and separate the volatiles from the water in products blown off from locomotives, and also to store said water for washout purposes; a second compartment adapted to store filling water, said compartments having confines which render them substantially tight against the escape of volatiles, including a common top confine and a common partitioning confine which terminates above the maximum water level of either compartment but below the common top confine, and leaves between said compartments a horizontally extensive passageway permitting free flow from the first compartment to the second compartment of volatiles disengaged in said first compartment, and the confines of and the water surface in said second compartment constituting a surface condenser for said volatiles; and a condenser receiving and delivering as condensate to the second compartment, volatiles that are not precipitated by said surface condenser; said compartments constituting parts of a substantially unitary structure, and their partitioning confine comprising an arcuate wall which leaves the compartments in heat transfer relation one to the other.

8. A locomotive boiler washing and refilling apparatus, comprising a first compartment adapted to receive and separate the volatiles from the water in products blown off from locomotives, and also to store said water for washout purposes; a second compartment adapted to store filling water and having communication with the first compartment above the maximum water line of the compartments, said communication permitting free flow from the first compartment to the second compartment of volatiles disengaged in said first compartment, and the confines of and the water surface in said second compartment constituting a surface condenser for said volatiles; and a condenser receiving and delivering as condensate to the second

compartment, volatiles that are not precipitated by said surface condenser; said compartments being of annular form, concentric the second within the first, and having a common roof structure.

9. A locomotive boiler washing and refilling apparatus, comprising a first compartment adapted to receive and separate the volatiles from the water in products blown off

10 from locomotives, and also to store said water for washout purposes; a second compartment adapted to store filling water and having communication with the first compartment above the maximum water line of the compartments,

15 said communication permitting free flow from the first compartment to the second compartment of volatiles disengaged in said first compartment, and the confines of and the water surface in said second compartment

20 constituting a surface condenser for said volatiles; and a condenser receiving and delivering as condensate to the second compartment, volatiles that are not precipitated by said surface condenser; said compartments

25 existing as a substantially unitary structure, with the first compartment surrounding the second compartment, and having a common roof structure of conical form whereby the space above the compartments enlarges

30 toward the condensing area.

10. In locomotive blowoff, washout, and refill apparatus, a first compartment having a connection through which it receives blown off products from locomotives, said first

35 compartment constituting a combined washout water-storing and volatiles-disengaging space; a second compartment constituting a filling water-storing space; said compartments being separated up to a level higher

40 than the maximum water level of either compartment; and a roof structure enclosing both compartments and having a space beneath it through which volatiles disengaged in the first compartment flow freely into the

45 space above the water level in the second compartment; said roof structure having beneath it, and over the second compartment, a depending baffle wall that downwardly deflects volatiles flowing beneath the roof structure.

11. A locomotive blowoff, washout, and refill apparatus as described in claim 10, in which one of the compartments surrounds the other; the baffle wall is shaped to define an enclosed space beneath the roof; and there is in said enclosed space a fresh water condenser.

12. A locomotive blowoff, washout, and refill apparatus as described in claim 10, in which one of the compartments surrounds the other, the roof is approximately conical in shape, and there is at the apex of the cone a vertical condensing chamber having within it a water spray and an inwardly spaced vertical wall defining an annular space

through which volatiles arise to meet the water spray.

13. A locomotive blowoff, washout, and refill apparatus as described in claim 10, in which one of the compartments surrounds the other, the roof is approximately conical in shape, and there is at the apex of the cone a vertical condensing chamber having within it a water spray and an inwardly spaced vertical wall defining an annular space through which volatiles arise to meet the water spray; the said inwardly spaced wall depending beneath the uppermost portion of the roof structure.

14. A locomotive blowoff, washout, and refill apparatus as described in claim 10, in which one of the compartments surrounds the other, the roof is approximately conical in shape, and there is at the apex of the cone a vertical condensing chamber having within it a water spray and an inwardly spaced vertical wall defining an annular space through which volatiles arise to meet the water spray; the said inwardly spaced wall depending beneath the uppermost portion of the roof structure; and there being beneath said condenser a horizontal baffle.

15. In a locomotive terminal, a reservoir partitioned into compartments, a roof over said compartments, a condenser chamber 95 communicating with the space beneath said roof, a water spray in said condenser chamber, a by-pass leading from the space beneath the roof, to the upper portion of said condenser chamber, a thermostat in said by-pass, and a water supply for said spray, controlled by said thermostat.

16. In a locomotive terminal, a reservoir partitioned into compartments, a roof over said compartments defining a space above them, through which they communicate one with another, an upstanding condensing chamber communicating with the space defined by the roof, and including outer and inner walls between which vapors can rise to the upper portion of the condensing chamber, a water spray discharging into space within the inner wall, a vapor by-pass passage leading from the space beneath the roof into the upper portion of the condensing chamber independently of the space between the condenser walls, and a thermostat in said by-pass having communication through which it controls discharge of water into the condensing chamber.

17. In a locomotive terminal, a reservoir having a partition dividing it into inner and outer compartments, a pipe through which blown off products from locomotive boilers are discharged into the outer compartment, and a roof covering both said compartments; the upper portion of said partition terminating above the maximum water level of both compartments but below the said roof and thereby leaving a free space between the com-

partments through which volatiles flow from the outer compartment to the inner compartment; and said roof and the confines of the inner compartment constituting a surface condenser for volatiles disengaged in said outer compartment.

18. In a locomotive terminal, a reservoir divided into inner and outer compartments, a roof covering said compartments and providing a space through which they communicate one with another, and a pipe through which blown off products from locomotive boilers are discharged into an outer compartment of said reservoir; there being in said outer compartment, baffles adapted to concentrate sludge from the blown off products, and a washout water outlet outside of said baffles.

19. A locomotive boiler washing and re-filling apparatus, comprising a first compartment adapted to receive the volatiles from the water in products blown off from locomotives, and also to store said water for washout purposes; a second compartment adapted to store filling water and having communication with the first compartment above the maximum water line of the compartments, said communication permitting free flow from the first compartment to the second compartment of volatiles disengaged in said first compartment, and the confines of and the water surface in said second compartment constituting a surface condenser for said volatiles; and a condenser receiving and delivering as condensate to the second compartment, volatiles that are not precipitated by said surface condenser; said compartments being of annular form, concentric the second within the first, and having a common roof structure.

Signed at Chicago, Illinois, this 18th day of July, 1928.

LELAND G. PLANT.
